UNITED STATES PATENT OFFICE.

LOUIS GATHMANN, OF WASHINGTON, DISTRICT OF COLUMBIA.

PROCESS OF DISTILLING OR REFINING HYDROCARBON OILS AND SPIRITS.

SPECIFICATION forming part of Letters Patent No. 768,796, dated August 30, 1904.

Original application filed August 5, 1903, Serial No. 168,289. Divided and this application filed April 22, 1904. Serial No. 204,369. (No specimens.)

To all whom it may concern:

Be it known that I, LOUIS GATHMANN, a citizen of the United States, residing in Washington, District of Columbia, have invented 5 new and useful Improvements in Processes of Distilling or Refining Hydrocarbon Oils and Spirits, &c., of which the following is a specification.

This invention relates to an improved process of distilling or evaporating hydrocarbon oils and spirits, &c., and has for its object to render the process more expeditious and considerably cheaper.

Any suitable apparatus may be employed in carrying out my process, and in the accompanying drawings I have shown one form of apparatus, which I do, however, not desire to claim herein, as the apparatus and system is the subject-matter of another application for 20 patent, filed August 5, 1903, Serial No. 168,289, and of which this present application is a division.

In the drawings, which are merely illustrative, Figure 1 represents a perspective view, 25 partly in section, of a form of apparatus in which the process can be carried out. Fig. 2 is a plan view of the same. Fig. 3 is a vertical section of the still or evaporator.

In the drawings, 3 represents a still or evaporator located adjacent to a condenser 4, heater 5, rotary pump 6, and vacuum-pump 7. The still is located over a heater or furnace 8, which may be of any ordinary or preferred form.

35 9 is a vacuum flue or pipe.
9' is a manipulating-valve.

10 represents circulating-flues in the still.
11 is the flue connecting the still with the condenser.

40 12, 12', and 12'' are the eduction-ports for the condensates in the order of their volatility. 13, 13', and 13'' are the receptacles for said condensates. 14, 14', and 14'' are the eduction-ports of said receptacles.

45 15, 16, and 17 are the induction-ports for cooling medium for condenser 4. 18 is a regulating-valve for the same.

19 is the supply-pipe for the still 3, and 20 is the regulating-valve for the same.

21 is a thermometer, and 22 a vacuum-gage. 50
23 is a manhole.
24, 25, and 26 are compartments.
27 is a condenser, and 28 is an automatic vacuum-regulator.

In operation the process to effect a distillation of hydrocarbon oils and spirits is as follows: The still 3 may be supplied, through the pipe 19, with the valve 20 to regulate same. The vacuum-pump 7 is designed to cause any desired vacuum during the process of distillation and is regulated according to the indications of the vacuum-gage 22. The materials in the still are then heated to the required temperature necessary for the volatilization of the constituents to be separated therefrom, similarly as is done in present methods. When the desired heat and the desired vacuum are attained, the rotary pump 6 is set in motion to cause the circulation of the gaseous fluid through the heater 5, through the materials in the still 3, then through the flue 11 into the condenser 4, compartment 24, where the heaviest constituent is condensed and drawn off through the eduction-port 12. The gaseous fluid then passes on through condenser 4, compartment 25, where the next heaviest constituent is condensed and drawn off through eduction-port 12', and so on until all the constituents are condensed in the order of their volatility in the usual manner. The fluid current passes 75 through and beyond all the condensing-compartments and will be practically freed from the volatile constituents. It may then be returned into the rotary pump 6, completing one circuit. The heater 5, which may be of 80 any usual or preferred construction, is designed to restore the lost heat to the gaseous fluid before it again enters the still. When the lighter constituents have been sufficiently distilled, the heat of the contents of the still 90 3 is raised as may be desired until the next heavier constituent or constituents are distilled as desired. This operation is repeated until the distillation is practically completed. The condenser may be of any ordinary or 95 preferred construction, adapted for fractional condensation preferred, and may receive its cooling medium in the usual manner and is

supplied, as shown in the drawings, through the induction-ports 15, 16, and 17. Said cooling medium may consist of water or crude petroleum, the latter preferred, as said operation already partly heats it for the still 3 when one charge of the latter has been distilled. The fluid current mentioned circulating continuously during this operation may be atmospheric air or non-combustible gases, like 10 carbonic acid, nitrogen, &c. Closing the manipulating-valve 9' would discontinue the circuit, and in this event the rotary pump 6 could be dispensed with. It may not be necessary to maintain a circulation in a closed circuit at 15 all times, though a partial vacuum may be maintained by operating the vacuum-pump 7 and the automatic vacuum-regulator 28. The same fluid current need not be returned through the circuit continuously-- that is to 20 say, after the completion of one circuit said gaseous fluid may be blown into a large condenser and a fresh supply circulated through the system under any desired vacuum.

It is obvious that many modifications will 25 suggest themselves--for instance, as to the proper temperature to be applied while the process is in operation. In this process the same rule may be followed as is usually practiced in distilling petroleum, &c.--that is, the 30 lighter volatile constituents are first evaporated and the temperature is gradually raised step by step until all the volatile constituents are evaporated as may be desired. However, in this instance the vacuum, volume, and force 35 of the air or fluid current may be varied, as may be found most advantageous, at every stage of the operation and according to materials to be treated.

While I have described particularly the 40 process of distilling or evaporating hydrocarbon oils or spirits, it should, however, be understood that I do not limit my invention to these materials, as my process may be advantageously employed in the distillation or evaporation of various liquids.

I am aware that prior to my invention distillation and evaporation has been accomplished under a vacuum in conjunction with heaters, condensers, and vacuum - pumps. 45 Therefore I do not claim such a combination, broadly; but

What I claim as my invention, and desire to secure by Letters Patent, is—

1. The process of distilling or refining hydrocarbon oils or spirits which consists in 50 causing a circulation of a gaseous fluid under diminished atmospheric pressure through said liquid to be distilled or refined, causing a frac-

tional condensation of the distilled or refined product and returning said gaseous fluid 60 through said liquid under treatment.

2. The process of distilling or refining petroleum which consists in causing a circulation of a gaseous fluid under diminished atmospheric pressure through the petroleum to 65 be distilled or refined, gradually raising the temperature of said petroleum until all the volatile constituents are practically evaporated, causing a fractional condensation of the distilled or refined product and returning said 70 gaseous fluid through said liquid under treatment.

3. The process of distilling or refining hydrocarbon oils or spirits which consists in causing a circulation of a gaseous fluid under 75 diminished atmospheric pressure through the liquid to be distilled or refined, causing a fractional condensation of the distilled or refined product, restoring the lost heat to said gaseous fluid and returning same through said 80 liquid under treatment.

4. In the process of distilling or evaporating liquids, the process which consists in circulating a gaseous fluid under less than atmospheric pressure through a liquid and in a 85 closed circuit by means of a circulating-pump, and condensing absorbed vapors from said gaseous fluid prior to its entry into the pump, substantially as described.

5. In the process of distilling or evaporating liquids, the process which consists in circulating a gaseous fluid under less than atmospheric pressure through a liquid and in a closed circuit by means of a circulating-pump, condensing absorbed vapors from said gaseous 95 fluid prior to its entry into the pump, reheating said gaseous fluid and returning the same through said liquid under treatment, substantially as described.

6. In the process of distilling or evaporating liquid, the process which consists in circulating a gaseous fluid through the liquid, in a closed circuit, by means of a circulating-pump; maintaining said gaseous fluid below normal atmospheric pressure by means of a 100 vacuum - pump; condensing the evaporated constituents, and returning said gaseous fluid through said liquid under treatment, substantially as described.

In testimony whereof I have signed my name 110 to this specification in the presence of two subscribing witnesses.

LOUIS GATHMANN.
